UNITED STATES PATENT OFFICE

DONALD F. SPROUL, OF CHICAGO, ILLINOIS, ASSIGNOR TO CARDWELL WESTINGHOUSE COMPANY, A CORPORATION OF DELAWARE

CUSHIONING DEVICE

Application filed October 30, 1929. Serial No. 403,423.

The invention relates to the friction spring type of cushioning device in which there is employed a helical spring formed of a rod of square section, or at least flattened on that 5 side which will constitute the inner periphery of the spring.

The principal object of the invention is to secure high efficiency in devices of this character.

10 While the invention is applicable to other uses, such as a car bolster support, it is shown and specifically described as a draft gear for railway cars.

In the disclosed embodiment of the invention, which, however, is not the only form it may take, the spring constitutes the outer casing which encloses the other elements of the gear, and segmental tapering friction shoes engage the inner face of the spring, 20 cooperating with a pair of segmental wedging shoes which in turn are in wedging engagement with a central thrust member.

In the drawings:

Fig. 1 is a detail central vertical longitudinal section through the underframing of a car showing the improved gear applied thereto;

Fig. 2 is a view on the line 2—2 of Fig. 1;

Fig. 3 is a central longitudinal plan section of the gear, the associated followers being shown in detail;

Fig. 4 is an end view of the gear;

Fig. 5 is a sectional view on the line 5—5 of Fig. 3;

35 Figs. 6 to 9 are views in perspective of various elements of the gear; and

Fig. 10 is a detail sectional view of a pair of cooperating wedges employed in the gear.

40 A pair of center or draft sills of a railway car are shown at 15, 15, and, as usual, carry draft and buffering lugs 16, 17, with which cooperate a pair of followers 18, 19. The gear is enclosed within a yoke 20 of usual construction, and comprises a helical spring 21, which is shown as formed of a rod rolled to square section so that the inner face of the spring may present a cylindrical surface.

45 This spring encloses as an outer casing the remaining elements of the gear, and has bear-

ing, through a spring seat, upon one follower, as 19, only.

A central thrust member 22 seats against the follower 18, opposite to the one engaged by the spring, and extends along the axis of the gear, its length being such that upon full compression it serves as a limiting stop. The element 22 is provided with two pairs of forwardly facing and inwardly inclined wedges 23, 24, which cooperate with complementary 55 wedges 25, 26, formed on the inner faces of a pair of segmental friction shoes 27, the rear ends of which are outwardly flanged, as shown at 28, to engage over a spring seat 29. At least one of the cooperating wedge faces, 60 as 23, is grooved in the direction of travel, insuring frictional contact and providing for the free discharge from between the wedges of the abraded material.

When, as in the device as illustrated, two 70 sets of wedging surfaces are arranged in tandem the grooving of these faces has the additional advantage that it quickly provides for uniformity of contact of the two sets of wedges in the event that in the manufacture 75 the wedge faces on each or either element are somewhat out of parallel or otherwise distorted. In the manufacture of devices of this character it is impracticable to resort to machining, and the cast elements are, 80 therefore, put into service as they come from the mold and are consequently rough and may be somewhat distorted. Where there are two sets of wedging surfaces on a single element, as in the present instance, any such 85 distortion causes unequal action, all or the major portion of the load being borne by one of them, causing undue wear thereof. By making the surface other than strictly flat, as by grooving, such wear is accentuated and 90 furthermore, the metal will be caused to flow into the depressions, thereby speedily bringing the companion wedge into service.

As soon as the set of wedges which have been thus in engagement are worn to conform to the other set of wedges, all of the wedges are subjected to the same pressure and wear uniformly.

Interposed between each of the friction shoes 27 and the inner face of the spring 21

is a tapering segmental friction shoe 30, the outer end of which is provided with an outstanding lateral flange 31, taking over a spring seat 32 at the end of the gear which 5 engages the follower 19. A bolt 33, setting axially through the thrust element 22 and into a retaining element 34, which engages the seat 32, binds the elements of the gear together for convenience in shipment 10 and installation. While the elements 32 and 34 are shown as separate castings, they may obviously be formed as a single element.

In assembling the device the spring is seated against the follower 32; the elements 15 22 and 27 are assembled and inserted within the spring, which is then compressed without bringing the wedges into action, and the elements 30 are inserted through the 20 openings in the follower 32, and the bolt 33 is now applied. The spring being relieved the parts assume the relative positions as shown in Fig. 3.

In buff, the follower 18 is forced inwardly by the draw-bar, wedging the shoes 28 25 laterally outward against the tapering shoes 30, and also carrying them forward, causing the compression of the spring and developing friction between the coils of the spring and the shoes 30, and between the latter shoes 30 and the shoes 27. The tapering form of the shoes 30 greatly augments the radial pressure, causing the wedge faces of the shoes 27 to creep forwardly on the wedging faces 35 of the thrust element, thereby still further compressing the spring. Prompt release is insured by the expansive force of the spring, but is sufficiently retarded by the friction of the parts.

In draft, the follower 19 is moved forwardly, carrying with it the spring seat 32 40 and the tapering shoes 30. The pressure of the spring upon the flanges 28 of the shoes 27 urge the latter forwardly, thus setting up a wedging action between these shoes and the thrust member and limiting the longitudinal movement of the shoes. The advance 45 of the tapering shoes increases the wedging action and the compression of the spring. The wedge faces 23, 24, are shown as grooved 50 longitudinally, thereby securing increased durability by providing for a displacement of the metal under severe pressure and thus lessening the tendency to wear.

In practice, the elements 27 will be case 55 hardened, the element 22 being of softer material. In service, the wedge faces as 24, 26 may not bear upon each other uniformly throughout their entire areas, because of mis- 60 placing or distortion of the draft lugs, or other parts of the structure and excessive pressure upon one portion of the softer wedge, as 24, will cause the metal to flow into the grooves, thereby changing the angle of the 65 wedge face transversely and bringing its en-

tire face into bearing upon the cooperating wedge.

A plurality of sets of wedges are advisable in a draft gear because of its length in order to distribute and equalize the lateral pressure. 70 In devices, such as bolster supports and the like, where the overall length is comparatively short, a single set of wedges will serve.

I claim as my invention—

1. In a cushioning device, in combination, 75 a follower, a thrust element opposed to the follower and having spreading wedge surfaces, a tie-rod connecting the follower and thrust element, segmental friction shoes cooperating with the wedge surfaces of the thrust element and having radially projecting flanges at their rearward ends, a helical spring reacting between the shoe flanges and the follower, and friction shoes interposed 80 between the first-named shoes and the spring, the follower being apertured for the insertion of the second-named shoes and such shoes having radially extending flanges at their outer ends engageable with the outer face of the follower.

2. In a cushioning device, in combination, 85 a follower, a thrust element opposed to the follower and having spreading wedge surfaces, segmental friction shoes cooperating with the wedge surfaces of the thrust element 90 and having radially projecting flanges at their rearward ends, a helical spring reacting between the shoe flanges and the follower, and friction shoes interposed between the first-named shoes and the spring, the follower being apertured for the insertion of the second-named shoes and such shoes having radially extending flanges at their outer ends engageable with the outer face of the follower.

In testimony whereof I affix my signature.

DONALD F. SPROUL.
